UNITED STATES PATENT OFFICE.

CHARLES WILLMS, OF BALTIMORE, MARYLAND, ASSIGNOR TO WILLMS SANITARY WORKS, INCORPORATED, OF BALTIMORE, MARYLAND, A CORPORATION OF DELAWARE.

FLUSHING-TANK.

No. 894,092.

Specification of Letters Patent.

Patented July 21, 1908.

Application filed April 23, 1907. Serial No. 369,719.

To all whom it may concern:

Be it known that I, CHARLES WILLMS, a citizen of the United States of America, residing in Baltimore city, State of Maryland, ⁵ United States of America, have invented certain new and useful Improvements in Flushing-Tanks, of which the following is a specification.

My present invention relates particularly ¹⁰ to the devices for operating the flush valves of what are known as "low-down" flushing tanks for water closets, etc.; but it involves also improved means for attaching the cover to the tank.

¹⁵ In low down tanks the valve is usually operated by means of a handle or push button located at the lower right hand corner of the tank, and it is sometimes located in the upper middle portion of the front wall of the ²⁰ tank. When located in this last mentioned position, it is necessary for the user of the closet to bend rearward and operate the button with his back. This is an unnatural movement and not always desirable. In the ²⁵ case first mentioned where the button is located at the lower right hand corner of the tank, the head of the button has been made relatively small and has been operated by the hand of the user of the closet. To do this it ³⁰ is necessary to bend the arm backward and turn the hand in an unnatural way to find the button.

According to my invention, I have provided means for operating the flush valve ³⁵ which can be actuated by an easy and natural movement of the arm without bending the back or twisting the hand.

My improvements are especially designed ⁴⁰ for use in connection with an enameled sheet metal tank such as shown in my Patent No. 838,601 of December 18, 1906, in which the water-containing tank is surrounded by a jacket or condensation collector between which and the tank there is an air space preventing condensation on the jacket. Such ⁴⁵ space between the front walls of the jacket and the tank, I utilize for mounting part of the lever connections between the actuating lever and the valve.

⁵⁰ The cover of the tank is arched so as to accommodate part of the valve operating mechanism, and in order to conveniently connect the cover with the jacket, I form the top of the latter with an outwardly projecting flange on its opposite sides and at its front,

and in the front portion of the flange I form a downwardly projecting extension constituting part of a lock for holding the cover in place. The cover, which is concavo-convex or arched, is formed at the sides and at the ⁶⁰ front with a downwardly projecting flange, the front portion of which has an inturned extension which interlocks with the extension on the front flange of the jacket. The rear corners of the cover are detachably connected to the jacket by means of screws or bolts. ⁶⁵

In the accompanying drawings,—Figure 1 is a perspective view of a flush tank embodying my improvements, some parts being broken away in order to better illustrate other parts. Fig. 2 is a perspective view of the tank showing its relation with a water closet seat. Fig. 3 is a perspective view of the cover looking at the inside. Fig. 4 is a perspective view of the tank with the cover removed. Fig. 5 shows a vertical transverse section of the tank with its cover attached, and Fig. 6 is a perspective view on an enlarged scale of the valve actuating lever and the horizontally arranged lever with which it is immediately connected.

The water-containing tank, A, is of substantially the same construction as that illustrated in my patent before mentioned, and the jacket or condensation collector, B, is also of the same general kind. The cover, C, is concavo-convex or arched, as shown, to accommodate certain parts of the valve-operating mechanism. At the top the jacket is formed with a down-turned rim portion, b, at the rear, and with a horizontal outwardly projecting flange, b', at the top of its sides and front. At the front the flange, b', is formed with a downwardly projecting extension, b². The cover, C, has no flange at its back edge, but it is formed at the edges of its sides and front with a downwardly projecting flange, c, which at the front is formed with an inwardly projecting extension, c', ⁹⁰ adapted to interlock with the extension, b², of the flange, b', of the jacket. The front flange and its extension are preferably curved as shown in order to better take enamel and produce a more pleasing appearance. In ⁹⁵ connecting the cover with the jacket the former is first placed over the latter and the extension, c', of the flange, c, is made to interlock with the extension, b², of the flange, b', then the rear end of the cover is properly ¹⁰⁰ 111

located and the opposite rear corners thereof are attached to the opposite rear corners of the top of the jacket. The tank, A, is so held in the jacket, B, as to provide an air space, X, between them. The tank is connected with the flush pipe, D, by suitable couplings, E, preferably such as those shown, and the jacket is connected with the flush pipe by a branch pipe, F.

10 The flush valve, G, is provided with a vertical, stem, g, which extends through a guide bracket, H, attached to the front wall of the tank, and the upper end of the stem is loosely connected with a vertical rod, I, the 15 upper end of which is jointed to a lever, J, extending horizontally toward one end of the tank and pivoted at, j, to the front wall of the latter near its upper end. This lever, J, is arranged inside the tank and it has an 20 arm, J', extending over the top edge thereof, its outer or front end being adjustably connected with a vertical rod, K, which extends down through the space X, between the jacket and the tank and has its lower end 25 jointed to one end of a horizontally arranged lever, L, arranged in the space, X, and extending to the opposite side of the tank, being pivoted at l to the front wall of the tank. The rod, I, is connected with the longer arm 30 of the lever, J, and the rod, K, is connected with the longer arm of the intermediate lever, L.

The device for actuating the valve-operating levers is located at the lower corner of 35 the tank on that side next the right arm of the user of the closet. Instead of using a vertically sliding push rod operated by hand, as is common, I employ a lever, M, which is hinged to a bracket, N, applied to the front 40 wall of the jacket. One arm, m, of this lever extends rearwards beneath the adjacent end of the lever, L, while its other or front arm is formed with an arm rest, m', of such extended area that the elbow of the user of 45 the closet may, without discomfort, be placed on it and move it downwards in such manner as to raise the short arm of the lever, L, pull down the short arm of the lever, J, and raise the flush valve, G. When the arm 50 of the user is withdrawn the parts assume their normal position after the proper lapse of time, the weight of the valve causing such movement. The arm rest is located some distance forward from the front wall of the 55 tank so as to be in convenient position to receive the elbow of the user of the closet.

It will be observed that the user of the closet can actuate the lever, M, very easily and without any unnatural movement of the back or twisting of the arm or hand. The 60 leverage is such as to cause the mechanism to operate easily and there is no danger of leakage, for, it will be observed, the lever, L, and the rod, K, are located in the space between the tank and its jacket, the lever, L, 65 is pivoted to the tank and the lever, M, is arranged some distance above the bottom of the jacket so that any water which overflows from the tank into the jacket and all water of condensation and after fill water which 70 enters the jacket will flow out through the pipe, F, to the flush pipe before rising to the level of the lever, M.

I claim as my invention:—

1. The combination of a water-containing 75 tank, a condensation collector associated therewith, a flush-valve within the tank, an actuating lever hinged to the front wall of the condensation collector and provided with an arm-rest to receive the elbow of the user 80 of the closet, an intermediate lever pivotally mounted in the space between the condensation collector and the lower part of the tank and which is operated by said actuating lever, a lever pivoted to the tank and connected with the flush-valve and a rod connecting 85 said lever with the intermediate lever.

2. The combination of a water-containing tank, a jacket surrounding it, a flush valve 90 within the tank, an actuating lever hinged to the front wall of the jacket, an intermediate lever in the space between the jacket and the tank which is operated by said actuating lever, and operative connections between said intermediate lever and the valve. 95

3. The combination of a water-containing tank, a jacket surrounding it, and between which and the tank there is an air space, a lever within the tank pivoted to the front wall thereof and having an arm projecting over the 100 top of the tank, a flush valve with which said lever is connected, an intermediate lever within the air space between the jacket and the tank, a rod connecting this lever with the arm of the first mentioned lever, and an actuating lever engaging the intermediate lever. 105

In testimony whereof, I have hereunto subscribed my name.

CHARLES WILMIS.
